UNITED STATES PATENT OFFICE

116,035

DESIGN FOR A BOWLING ALLEY

Leo J. Kelly, Chicago, Ill., assignor to The Exhibit Supply Company, Chicago, Ill., a corporation of Illinois

Application April 19, 1939, Serial No. 84,381

Term of patent 3½ years

To all whom it may concern:

Be it known that I, Leo J. Kelly, a citizen of the United States and a resident of Chicago, in the county of Cook and State of Illinois, have invented a new, original, and ornamental Design for a Bowling Alley, of which the following is a specification, reference being had to the accompanying drawing, forming a part thereof, and in which the single figure is a perspective view of a bowling alley showing my new design.

I claim:

The ornamental design for a bowling alley, as shown.

LEO J. KELLY.
